(57) **CLAIM**

The ornamental design for a rear cover for construction machine, as shown and described.

DESCRIPTION

FIG. 1 is a perspective view of a rear cover for construction machine;

FIG. 2 is a front view thereof;

FIG. 3 is a right side view thereof; and,

FIG. 4 is a top view thereof.

The broken lines depict portions of the rear cover for construction machine in which the design is embodied that are not considered part of the claimed design.

The dashed lines show a boundary between the claimed design and unclaimed portions.
